Specification for Design.

Patented Sept. 22, 1914.

Application filed July 27, 1914. Serial No. 853,480. Term of patent 3½ years.

To all whom it may concern:

Be it known that I, JOHN J. NASH, a citizen of the United States, residing in Waterbury, in the county of New Haven and State of Connecticut, have invented a new, original, and ornamental Design for a Shower-Plate, of which the following is a specification when taken in connection with the accompanying drawing.

In the drawing, Figure 1 is a face view

of a shower plate embodying my design; and Fig. 2 is an edge view of the same.

What I claim is:—

The ornamental design for shower plate, substantially as shown.

JOHN J. NASH.
